UNITED STATES PATENT OFFICE.

CLAYTON O. SMITH, OF WORCESTER, MASSACHUSETTS, ASSIGNOR TO
NORTON EMERY WHEEL COMPANY, OF WORCESTER, MASSACHU-
SETTS.

GRINDING-MACHINE.

No. 839,080.

Specification of Letters Patent.

Patented Dec. 18, 1906.

Application filed October 31, 1904. Renewed October 22, 1906. Serial No. 340,072.

To all whom it may concern:

Be it known that I, CLAYTON O. SMITH, a citizen of the United States of America, and a resident of the city and county of Worcester, State of Massachusetts, have invented 5 certain new and useful Improvements in Grinding-Machines, of which the following is a specification.

This invention relates to grinding-ma- 10 chines, and especially to machines for grinding ball-races in ball-bearings.

Heretofore, so far as I am aware, it has been customary to grind ball-races for the purpose of giving them their desired contour 15 by means of a shaped emery or abrasive wheel—that is, an emery-wheel having a grinding-face of shape which it is desired to give to the ball-race. Another well-known method of securing the desired contour of the 20 ball-race is to employ pattern guide-plates, by means of which devices governing the bodily movement of the grinding-wheel are led over the pattern and the grinding-wheel thereby bodily moved from one point to an- 25 other of the surface to be ground. The first of these methods necessitates the repeated repairing or truing up of the grinding-wheel, as is obvious, while the second necessitates a 30 useless and complex multiplicity of expensive parts which entail a constant expense for their renewal and repairs.

In the present invention I obviate both the necessity of requiring a shaped wheel for grinding ball-races and the use of pattern 35 guide-slides by so mounting the abrasive wheel that the portion of the abrasive face thereof which engages the work can be moved in a curvilinear path while in contact with the work and at the same time that the 40 wheel is rotating about its axis, the contour of the path corresponding to the cross-sec- tional contour of the ball-race.

In the preferred form of my invention I 45 mount the abrasive wheel to swing about an axis having an angular relation to the axis about which said wheel rotates and provide means for oscillating the wheel about said axis during the grinding operation. This causes that portion of the abrasive face of 50 said wheel which engages the work to swing back and forth in the arc of a circle, and by giving said wheel a rotary motion about its axis and at the same time the swinging mo- tion above referred to the desired contour

may be given the ball-race without regard to 55 the shape of the face of the wheel.

In the accompanying drawings, Figure 1 is a rear view of a machine embodying my invention. Fig. 2 is a side view thereof. Fig. 3 is a top plan view. Fig. 4 shows details of 60 the traversing mechanism for the carriage which supports the abrasive wheel. Fig. 5 is a detail of the shoe forming a part of the traversing mechanism. Fig. 6 is a view showing the principle on which my invention 65 operates. Fig. 7 is a front view of an annulus having a ball-race ground therein.

Referring first to Figs. 6 and 7, which show an annulus having a ball-race ground therein, 70 3 designates said annulus having a ball-race 4 in one face thereof, said ball-race constituting the way in which the balls of a ball-bearing travel when this part is assembled with the other parts constituting said ball-bearing. It is necessary, of course, that the 75 cross-sectional curvature of said ball-race should be a true arc of a circle, and to give said ball-race this desired contour I mount the emery or abrasive wheel, which is shown in edged view at 5, Fig. 6, so that said wheel 80 can swing bodily about an axis having an angular relation to its axis of rotation. In this embodiment of my invention the axis about which the abrasive wheel swings bodily stands at right angles to the axis of rotation 85 of said wheel, and in Fig. 6 is designated by the point 6, which point also coincides with the center of the arc of curvature of the ball- 90 race 4. Referring to said Fig. 6, it will be obvious that if the abrasive wheel 5 is swung 95 from the full-line position to the dotted-line position about the axis 6 at the same time that said wheel is rotated about its own axis the ball-race will be ground on the arc of a circle whose center is the point 6, regardless 95 of the shape or contour of the face of the abrasive wheel.

In the embodiment of my invention shown in Figs. 1, 2, and 3, the abrasive wheel 5 is mounted in suitable bearings 7, carried by a 100 wheel-stand 8, said stand in turn being supported by a carriage 9, suitably supported upon the frame 10^a of the machine to turn about the point 10 as an axis. The carriage 9 may be oscillated about its axis 10 by any 105 suitable means, that herein shown comprising an endless screw 11, journaled in suitable bearings in the frame 10^a. Coöperating

with the groove 12 of said screw is a shoe 13, which is journaled in a block 14, mounted to slide in suitable ways 15 in the frame. Pivoted to said block 14 is a link 16, which is 5 also pivotally connected with the carriage 9, as at 17. With this construction it will be obvious that rotation of the endless screw 11 will cause the shoe 13 to traverse back and forth in the groove 12, and the movement of 10 said shoe through the link 16 will oscillate the carriage 9 about its axis 10. 51 designates a guard which is carried by the block 14 and operates as a cover for the guideway in which the block 14 moves. This form 15 of traverse mechanism for the carriage is not essential, however, and any other suitable means for oscillating said carriage may be used without departing from the invention.

I prefer to adjustably mount the wheel- 20 stand 8 upon the carriage 9, thereby making the machine capable of adjustment for grinding ball-race grooves of different sizes, as will be more fully explained hereinafter. The adjustment of the wheel-stand 8 upon the 25 carriage may be effected in any suitable or usual way, as by an adjusting-screw 18, having a hand-wheel 19 thereon, by means of which said wheel-stand may be adjusted.

My improved machine also includes a 30 suitable work-support on which is supported the piece or element in which the ball-race is to be ground. The particular construction of work-support may be varied according to the shape of the piece to be supported thereby. In the embodiment of my invention 35 herein illustrated the work-support is adapted to sustain an annulus such as shown in Figs. 6 and 7, and it comprises a suitable chuck device 20 of any appropriate construction, adapted to hold said annulus 3. This 40 chuck device is rigid therewith and is driven by a gear 21, meshing with a pinion 22 upon a shaft 23; said shaft having a driving-pulley 24 thereon and being mounted in suitable 45 bearings in a stand 25. The work-holder is preferably adjustable both toward and from the abrasive wheel and laterally with respect thereto, and for this purpose I have mounted the stand 25 to slide on ways 26 on a carriage 50 27, and said carriage in turn is mounted to slide on suitable ways 28 on the main frame 10. The ways 26 28 are arranged at right angles to each other, thus permitting the work-holder to have the desired movement 55 toward and from the abrasive wheel and also laterally thereof. Any suitable or usual adjusting-screws 29 and 30 are provided for adjusting the carriage 27 on its ways and the stand 25 on said carriage.

60 The shaft carrying the endless screw 11 and also the shaft 23 for driving the chuck device may be driven in any suitable way. As herein illustrated they are driven from the same power-shaft, and for this purpose 65 said power-shaft, which is designated by 31,

has thereon a pulley 32, which is belted to a pulley 33, carried by the shaft 34, on which said endless screw 11 is mounted, and said power-shaft also has thereon another pulley 36, which is belted to and drives a pulley 37, 70 fast on said shaft 23. I prefer to mount the pulley 33 loosely on the shaft 34 and to provide suitable clutch mechanism 38 for clutching said pulley to the shaft at the appropriate time. Any other way of driving the 75 shafts 34 and 23 may be employed, however, without departing from my invention.

I have herein shown my machine as equipped with any suitable or usual pump mechanism 40 for delivering water through 80 the pipe 41 to the abrasive wheel for keeping said wheel cool. The abrasive wheel may be driven in any suitable way, such as by means of belt 44, connected to some overhead shafting.

In grinding a ball-race in an annulus, such as shown in Figs. 6 and 7, said annulus is first clamped to the chuck device 20, and the face 48, in which the ball-race is to be ground, is trued up on the abrasive wheel by moving 90 the stand 25 back and forth upon the ways 26 and at the same time rotating said chuck device. During this operation the clutch 38 is disengaged, and therefore the carriage 9 has no oscillatory movement, and the abrasive wheel may have any desired position, although I prefer to place it substantially in the position shown in Fig. 3. After the face 48 has been trued up the carriage 27 is adjusted so as to position said face a distance 95 from the axis 10 equal to the length of radius of the curvature of the ball-race to be ground minus the depth of said ball-race. In practice these ball-races are usually ground to the depth of one-eighth of an inch, and therefore 100 the work-support is adjusted so as to bring the face 48 a distance from said axis 10 equal to the radius of the curvature of the desired ball-race less one-eighth of an inch. Assuming that the ball-race is to be ground on 105 an arc of a circle whose radius is three-quarters of an inch, the work-support will be adjusted to bring the face 48 three-quarters of an inch minus one-eighth of an inch, or five-eighths of an inch from the axis 10. The 110 stand 25 is then adjusted upon the carriage 27 to move the annulus laterally to bring the face thereof opposite the abrasive wheel, and said abrasive wheel is then adjusted until the portion thereof which engages the work will 115 be projected beyond the axis 10 a distance equal to the radius of curvature of the desired ball-race. The machine is then set into operation and the clutch 38 thrown into engagement. The rotation of the shaft 34 will 120 cause the carriage 9, and consequently the abrasive wheel, to oscillate about the axis 10, and the rotation of the shaft 23 will cause the annulus to turn about its axis. These combined movements result in grinding the ball- 125 130

race to the desired curvature, as seen in Figs. 6 and 7, and this curvature is obtained without any regard to the exact contour of the face of the grinding-wheel. It is unnecessary, therefore, to be constantly truing the abrasive wheel, and the grinding operation can be proceeded with rapidly and with absolute certainty.

The principal feature of my invention is the mounting of the abrasive wheel so that it will swing bodily about an axis having an angular relation to its axis of rotation, thereby moving that portion of the abrasive face thereof in a curvilinear path corresponding to the curvilinear cross-section of the ball-race to be ground, and believing that I am the first to devise a machine having this feature I desire to claim it broadly. The particular manner of mounting the wheel so as to obtain this swinging movement, may be changed in various ways without departing from my invention. I would also remark that while the particular form of work-support illustrated is suitable for supporting an annulus in which a ball-race is to be ground, yet my invention is not limited to this construction, as the shape and details of the work-support will be varied to suit the shape and character of the work to be supported thereby.

Having described my invention, what I claim as new, and desire to secure by Letters Patent, is—

1. In a grinding-machine, an abrasive wheel and means to rotate said wheel simultaneously in two intersecting planes of rotation while the grinding portion of the wheel is engaging the work.

2. In a grinding-machine, an abrasive wheel and separate means for simultaneously rotating said wheel in two planes of rotation at right angles to each other while the operative portion of the wheel is in engagement with the work.

3. In a grinding-machine, an adjustably-mounted abrasive wheel, rotating means therefor, and means to shift the position of the wheel pivotally while in contact with the work, thereby moving the portion of the wheel which engages the work in a curvilinear path.

4. In a grinding-machine, an abrasive wheel, rotating means therefor, and means to swing said wheel about an axis having an angular relation to its axis of rotation while the wheel is engaging the work.

5. In a grinding-machine, an abrasive wheel, rotating means therefor, means to swing said wheel about an axis having an angular relation to its axis of rotation while said wheel engages the work and means to adjust said wheel relatively to the axis about which it swings.

6. In a grinding-machine, an abrasive wheel, rotating means therefor, and means to

swing said wheel about an axis at right angles to its axis of rotation while the wheel engages the work.

7. In a grinding-machine, an abrasive wheel, rotating means therefor, means to swing said wheel bodily about an axis having an angular relation to its axis of rotation while the wheel is in engagement with the work and means to adjust said wheel toward and from the axis about which it swings.

8. In a grinding-machine, a carriage mounted to swing in the arc of a circle, means for oscillating said carriage, and an abrasive wheel mounted on said carriage to oscillate therewith, the oscillation of the carriage moving the portion of the face of said wheel which engages the work in an arc of a circle while the wheel portion is in such engagement.

9. In a grinding-machine, a carriage, an abrasive wheel adjustably mounted upon said carriage and means to move said carriage in a curvilinear path while said abrasive wheel is in engagement with the work.

10. In a grinding-machine, an oscillating carriage mounted to swing about an axis, an abrasive wheel mounted on the carriage and adapted to engage the work under operation while said carriage is being oscillated means to adjust said wheel with relation to the carriage toward and from the axis of oscillation of the carriage, and rotating means for the wheel.

11. In a grinding-machine, a carriage adapted to oscillate about an axis of oscillation, means to oscillate said carriage, said means including an endless screw, an abrasive wheel mounted on the carriage and rotating about an axis which has an angular relation to the axis of oscillation, and rotating means for said wheel.

12. In a grinding-machine, an abrasive wheel, means to rotate said wheel, means to swing said wheel about an axis having an angular relation to its axis of rotation while said wheel is in engagement with the work under operation a work-holder, and means for moving the same to advance the work with reference to the abrasive wheel.

13. In a grinding-machine, a work-holder, an abrasive wheel, means to give the work-holder and abrasive wheel a relative movement, and means to swing said wheel about an axis having an angular relation to its axis of rotation during the time that the wheel is in engagement with the work.

14. In a grinding-machine, work-support, an abrasive wheel, rotating means for said wheel, and means to swing said wheel while in engagement with the work about an axis extending parallel to the face of the work on which said wheel is operating.

15. In a grinding-machine, an abrasive wheel, rotating means therefor, means to swing the wheel bodily about an axis having

an angular relation to its axis of rotation while the operating portion of the wheel is in engagement with the work a work-support, and means to adjust said work-support both 5 toward and from said first-named axis, and laterally with respect thereto.

16. In a grinding-machine, a rotating work-holder, means for rotating said work-holder, an abrasive wheel, rotating means 10 therefor, and means to swing said wheel about an axis having an angular relation to the axis of rotation of the work-holder while the said abrasive wheel is engaging the work.

17. In a grinding-machine, a rotating work-holder, means to rotate said work-holder, an abrasive wheel, rotating means therefor, and means to swing said wheel while in contact with the work about an axis at right angles to the axis of rotation of the work-holder.

Signed by me at Worcester, Massachusetts, this 26th day of October, 1904.

CLAYTON O. SMITH.
